UNITED STATES PATENT OFFICE.

RHODA A. BURNS, OF SHREWSBURY, MASSACHUSETTS.

SAD-IRON HOLDER.

SPECIFICATION forming part of Letters Patent No. 417,228, dated December 17, 1889.

Application filed March 1, 1889. Serial No. 301,598. (Model.)

To all whom it may concern:

Be it known that I, RHODA A. BURNS, a citizen of the United States, residing at Shrewsbury, in the county of Worcester and State of Massachusetts, have invented certain new and useful Improvements in Sad-Iron Holders; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

15 The invention relates to that class of sad-iron holders which are provided with means for cleaning the starch from the bottom of the iron.

The invention consists in the particular construction and arrangement of the parts of the sad-iron holder, as hereinafter described, and pointed out in the claim.

20 Figure 1 is a plan view showing the sand-paper holder swung out from underneath the sad-iron holder. Fig. 2 is a longitudinal vertical section through the two holders closed up so that one is under the other.

In the drawings, A represents the sad-iron holder, with the legs a and handle a' . 25 A' is a corner projection to the sad-iron

holder, the same being vertically perforated at a^2 to receive a stud-pivot b , which turns therein, but is fixed in the corner projection B' of the sand-paper holder B. The latter is provided with four legs b^3 . The sand-paper 35 holder B has at each side a longitudinal slot b' , these two slots being parallel to each other, so as to properly receive the sand-paper, whose ends are pierced by the subjacent pointed studs b^2 , which are at about the longitudinal 40 middle of the part B. By this construction and arrangement of parts the sand-paper holder may be quickly thrown out and the adhering starch quickly taken from the bottom of the sad-iron. 45

Having thus described all that is necessary to a full understanding of my invention, what I claim as new, and desire to protect by Letters Patent, is—

The combination, with a sad-iron holder 50 having extension A' of the sand-paper holder B, pivoted to said extension and provided with the side slots b' , pointed studs b^2 , and legs b^3 , substantially as shown and described.

In testimony whereof I affix my signature in 55 presence of two witnesses.

RHODA A. BURNS.
